SAFETY DEVICE FOR FIREARMS

Ernst Altenburger, Oberndorf-on-the-Neckar, Germany, assignor to Mauser-Werke A.-G., Oberndorf-on-the-Neckar, Germany, a joint-stock company of Germany

Application August 20, 1935, Serial No. 37,093
In Germany August 20, 1934

12 Claims.

(Cl. 42—70)

This invention relates to a safety device for fire arms, and more particularly to a locking bolt for the firing pin of a pistol, a safety device, especially for pistols having a hammer and a trigger, 5 and to means connected to the hammer for preventing the access of dust and dirt to the interior of the pistol.

Safety devices for the firing pin are old in which the pin is shifted axially for moving it beyond reach of the hammer, or a check is provided for intercepting the hammer before it strikes the firing pin.

These old devices are departed from according to the invention, by separating the paths of the 15 firing pin and the member which strikes or releases the pin, i. e., by not only moving the pin beyond reach of the member, but also beyond the direction the member moves in. This is effected by moving the axis of the pin out of the position it occupies when the pistol is set at firing. By 20 these means, when the pistol, or arm, is at safety, the firing pin and the member are so far apart that unintentional firing by shocks or the like, is absolutely prevented.

25 Other features of the invention will appear from the following specification, the drawings and the claims.

The second safety device comprises means for lowering the hammer, and for arresting the hammer when the arm is at safety.

30 Safety devices are old in which the hammer can be lowered while the arm is at safety, but in such devices the hammer can not be arrested. On the other hand, a safety device for pistols has 35 already been proposed in which the hammer is lowered upon operation of the safety bolt for the firing pin, but again the hammer is not arrested in its lowered position. The last-mentioned device is unsatisfactory because the setting at safety, on the one hand, and the automatic lowering 40 of the hammer (which is under tension and strikes a check placed before the firing pin, or a similar part) on the other hand, are two operations which are normally supposed to exclude one another. The impression that the arm will be fired, is invariably connected with the striking of the hammer but if the hammer is lowered and strikes while the pistol is at safety, this may cause the operator to start. Lastly, a pistol 45 equipped with such a safety device cannot be carried in the pocket when cocked.

The pistol according to the invention is distinguished from the known art by a locking pawl which is under the control of the safety bolt of 50 the pistol and, when the pistol is at safety, locks

the lowered hammer against cocking, but does not lock the cocked hammer against lowering. The cocked hammer must be lowered from the trigger after the locking bolt of the pistol has been operated, i. e., the hammer is lowered by an extra manipulation, and the operator is not startled.

Another feature of the invention is that a locking pawl is pivoted on the hammer and cooperates with a spring catch. This catch is controlled by the safety device so as to allow the cocked hammer to be lowered, and, in turn, controls the locking pawl to which it presents an abutment.

Preferably, the safety device is a rotary bolt which when the arm is placed at safety, moves 15 the firing pin beyond the reach of the hammer.

Further features and details of the invention appear from the following specification and drawings showing a safety device by way of example.

According to another feature of the invention, the hammer, during its striking movement for firing a cartridge, not only closes the casing of the pistol for a certain distance, as in old structures, but the hammer is equipped with an extension opposite its striking face, and a cocking lug on the extension. The extension occupies an opening in the casing which completely encloses the hammer, and the opening is closed by the extension in the cocked and uncocked positions of the hammer. By means of suitable bridges at the casing, the opening for the movement of the hammer which was exposed heretofore, is now closed against dust and sand.

According to another feature of the invention, 35 the extension of the hammer is part of a circle about the pivot of the hammer, and moves in a groove adjacent the opening, so that only the cocking lug projects from the casing.

In automatic pistols for which the improvement is principally designed, the opening for the hammer extension is bordered at one end by a bridge at the breech, and at the other end by a bridge at the stock. The bridge at the breech is at the outer side of the arc-shaped hammer extension, and the bridge at the stock is at the inner side of the extension. The two bridges and the arc-shaped extension make up a perfectly tight closure of the casing in all positions of the hammer.

Other details and features of the invention will appear from the following specification, the drawings, and the claims.

The drawings illustrate, by way of example, a pistol equipped with a hammer and a trigger.

Figs. 1-5 show the safety device for the firing pin, Figs. 6-8 show the device for lowering and arresting the hammer, and Fig. 9 shows the hammer protected against dust.

5 Fig. 1 is a longitudinal section showing the pistol at safety.

Fig. 2 is a similar section showing the breech moving into firing position, and the spring catch disengaged from the hammer.

10 Fig. 3 is a similar section showing the lowering of the hammer while the pistol is at safety.

Figs. 4 and 5, respectively, illustrate the rotary safety bolt, and the spring catch of which Figs. 4a, 4b and 4c are sections taken on lines E-F, 15 A-B and C-D respectively of Fig. 4 and Fig. 5a is a section taken on line V-V of Fig. 5.

Fig. 6 is a longitudinal section of a pistol whose hammer and spring catch are in uncocked position.

20 Fig. 7 is a similar section showing the pistol at safety, and the hammer and the spring catch in the position in which the spring catch is thrown out and the hammer is operated by the trigger.

Fig. 8 is a section of the casing, viewed from 25 the front end of the pistol and showing the position of the locking pawl with respect to the hammer and the casing.

Fig. 9 shows the pistol with the specially designed hammer in longitudinal section.

30 The safety device for the firing pin is designed as follows:

Two shoulders 1 and 2 for supporting the firing pin 3 on the rotary safety bolt 4 (Figs. 1 and 2, and section A-B in Fig. 4b) rock the striking pin

35 3 beyond reach of the hammer or striking member 5 when the safety bolt has been turned through 90°. At the same time, a flange 6 on the firing pin is moved into a corresponding notch 7 in the bore of the breech, for holding the firing 40 pin against movement.

When the locking bolt is at safety, the hammer 5 cannot be cocked by pressing the trigger, or by handling the hammer, since the front arm 8 of the spring catch 9 is engaged and arrested 45 by the safety bolt.

Without extra provision at the safety device of the pistol, it could not be loaded when at safety. However, the hammer which was locked by the spring catch, is released by retracting the breech 50 for a short distance to move the safety bolt clear of the arm 8.

The hammer which has now become free again, is arrested after the breech has been fully retracted into cocking position, until the safety bolt 4 on the breech which now returns into firing position, engages the end of the rear arm 10 of the spring catch 9, thereby moving the spring catch 9 clear for the length x of its abutment, and the hammer, under the pressure of its spring, 60 fully throws out the spring catch 9 through an inclined face 11 connected to its tooth. The hammer follows the breech, but there is no danger in this movement, and finally it is locked, as described by the arm 8 of the spring catch engaging the safety bolt 4.

When the safety device is unbolted, the arms 8 and 10 of the spring catch 9 move freely through recesses in the rotary locking bolt 4. (Fig. 4c and 4a, sections C-D and E-F).

70 Means are provided for uncocking the cocked hammer while the pistol is at safety. Such means are very simple and do not involve extra members between the safety bolt and the spring catch. Just before the movement into safety 75 position has been completed, and the firing pin

has been moved out of the way of the hammer, a cam 12 (Figs. 3 and 4) at the bolt 4 strikes a lug 13 of the spring catch and thereby breaks the locking engagement of the catch 9 and the cocked hammer 5, so that now the hammer can return 5 into its uncocked position without risk.

The pistol illustrated in Figs. 6-8 is designed as follows:

The hammer 5 is mounted to pivot in the stock 15 of the pistol on a bolt 14. It cooperates with 10 a spring catch 17 fulcrumed at 16. The spring catch has an abutment 18 which is engaged by a tooth 19 on the hammer 5 when the hammer is moved into cocking position by hand or by the returning breech. A spring 20 tends to hold the 15 spring catch 17 engaged with the hammer. An arm 21 on the spring catch 17 cooperates with the rotary safety bolt 4 for the firing pin 3, and, when the firing pin is at safety, the arm 21 is engaged by the bolt 4 and limits the oscillation 20 of the spring catch 17 (Fig. 7) while when the firing pin 3 is unbolted, the arm 21 freely enters a notch 22 in the safety bolt (Fig. 6).

A pawl 23 is fulcrumed on one side of the hammer 5 at 24. A pin 25 at the free end of the pawl 25 engages in a hole 26 of the hammer whose inside diameter is larger than the outside diameter of the pin 25, and the oscillation of the pawl 23 is limited by the hole 26. The pawl 23 is inserted together with the hammer and is held in position by the wall at one side of the casing 15 (Fig. 8). The pawl 23 has a lug 27 which cooperates with a second abutment 28 at the lower side of the spring catch 17, as will now be described:

(a) *Pistol set at firing*

35

Obviously, when the pistol is set at firing, the pawl 23 at the hammer must be inactive. Therefore, when the hammer 5 is cocked by hand, or by the trigger, the pawl 23 is turned about its 40 pivot 24 toward the outer side (anti-clockwise) by the spring catch 17 whose second abutment 28 is engaged by the pawl, until the pin 25 bears against one side of the hole 26. When the hammer is moved further toward its cocking position, 45 the pawl 23 turns the spring catch 17 clockwise about its pivot 16. Finally, after its pivot 24 has been sufficiently displaced with respect to the position of the point where the pawl 23 engages the spring catch, the pawl moves back for some 50 distance into the hammer so that it clears the spring catch 17. The hammer which is cocked by hand or by the trigger when the pistol is set at firing, is free to move into firing position. The pawl 23 moves back into the hammer as far 55 as the hole 26 allows the pin 25 to move. The spring catch 17 is also moved beyond the path of the pawl 23 for some distance, and its arm 21 partly enters the notch 22 in the safety bolt 4.

(b) *Setting at safety with hammer in cocked position*

60

An important feature of the invention is the idea that the hammer must not be influenced by the operation of the safety device, in the present 65 instance, the rotary safety bolt 4, in such manner that it is automatically lowered when the safety device is operated; on the contrary: The hammer is lowered from its cocked position only by operating the trigger, for the reasons stated 70 above, while the pistol is at safety. The cocked pistol must be in such condition that it can be carried while at safety.

To this end, the spring catch 17 has a certain play for which it can be oscillated when the 75

safety bolt is in its active position. This play is just such that the spring catch can be moved to become disengaged from the hammer, by the trigger, and the lug 27 of the pawl 23 which moves inwardly as far as possible, clears the spring catch. As the firing pin 3 has been moved beyond the path of the hammer by the rotary safety bolt 4, the hammer, if it strikes, cannot fire a cartridge.

10 (c) Arresting the uncocked hammer when pistol is at safety

Another object of the invention is to provide a safety device by which the uncocked hammer is arrested upon operation of the safety device. The uncocked hammer is arrested with the pistol at safety by, on the one hand, positioning the point of attack of the second abutment 28 of the spring catch 17 with respect to the pivot 24 of the pawl 23, so that the spring catch 17 turns the pawl 23 in outward direction and anti-clockwise when it is attempted to cock the hammer, and, on the other hand, by the spring catch 17 engaging the perimeter of the rotary bolt 4 with its arm 21 after having been rocked for a short distance by the hammer. The spring catch is now arrested by the safety bolt 4 and thereby becomes an abutment for the pawl 23 on the hammer, preventing any further movement of the hammer in cocking direction.

If it is attempted to pull the trigger when the hammer is uncocked, it will be found that the trigger does not move since the hammer has been arrested. The operator immediately notices that the pistol has been set at safety. The pistol can only be cocked and fired after having been set at firing. Unintentional or involuntary manipulations which may cause errors and accidents, are practically eliminated by the described mechanism.

40 The design of the hammer according to Fig. 9 is as follows:

The hammer 5 has an arcuate extension 29, with a cocking lug 30 at its free end. Sealing bridges 31 and 32 are arranged, respectively, at the breech and at the stock. The uncocked position of the hammer is shown in full, and its cocked position is shown in dotted lines.

In both positions of the hammer 5, the mechanism is effectively sealed against sand and dust by the bridges 31 and 32 engaging the outer and the inner side, respectively, of the arcuate hammer extension 29. The hammer extension also closes completely the opening provided for the movement of the hammer, without interfering with its cocking and uncocking by the lug 30 projecting from the pistol.

I claim:

1. A safety device for fire arms comprising a striking member, a firing pin adapted to be moved beyond reach of the striking member by displacement relative to its axis, and means surrounding the firing pin and having a recess therein which is engaged by a part of the firing pin in its displaced position to hold the firing pin against axial movement.

2. A safety device according to claim 1, in which a safety bolt is provided which is rotatably mounted and engages the rear end of the firing pin and by its rotation is adapted to move the firing pin.

3. A safety device for fire arms comprising a striking member having a tooth thereon, a firing pin, a safety bolt rotatably mounted and engaging the rear end of the firing pin and by its

rotation is adapted to displace the rear end of the firing pin relative to its axis beyond reach of the striking member, and a spring catch having a front arm for cooperation with the safety bolt when the bolt is at safety and having a tooth thereon to contact with the tooth on the striking member to prevent movement of the striking member.

4. A safety device according to claim 3, in which the spring catch also has a rear arm adapted to be depressed and rocked with the catch until the tooth disengages, said rear arm being operated by the safety bolt a short time after a breech of the firearm has started returning from its fully retracted position so that the striking member can follow the advancing breech.

5. A safety device according to claim 3, in which the striking member is provided with an inclined face in cooperation with the tooth, and in which the spring catch is provided with an abutment the edge of which being placed adjacent the inclined face after the spring catch has been locked by the safety bolt moving forward with the breech, the inclined face being so positioned with respect to the edge of the abutment that the striking member under pressure of its spring effects the complete disengagement of the tooth from the abutment.

6. A safety device according to claim 1, in which an arm is provided adjacent a spring catch, and a locking bolt having a cam is provided for direct transmission an action causing cocking of the spring catch and uncocking the striking member from the bolt in its safety position.

7. A pistol comprising a striking member, a trigger, a safety member, a pawl between the safety member and the striking member and controlled by the safety member, and means whereby the pawl exclusively locks against cocking of the striking member when the pistol is set for safety and unlocked against uncocking the striking member.

8. A pistol according to claim 7, in which a spring catch is provided whereby the pawl is controlled from the safety member by the spring catch which is influenced to permit uncocking of the cocked striking member when the safety member is at safety and the spring catch being a controlling member and an abutment for the pawl.

9. A pistol comprising a striking member, a trigger, a safety member, a pawl between the safety member and the striking member and controlled by the safety member, said pawl having means for exclusively locking against cocking of the striking member when the pistol is set for safety and unlocked against uncocking the striking member, a spring catch whereby the pawl is controlled from the safety member by the spring catch which is influenced to permit uncocking of the cocked striking member when the safety member is at safety and the spring catch being a controlling member and an abutment for the pawl, and two checks between which the pawl is free to pivot on the striking member.

10. A pistol comprising a striking member provided with an extension and a lug on the extension on that part of the striking member which is opposite to the striking face, a trigger, a safety member, and a pawl between the safety member and the striking member and controlled by the safety member, said pawl exclusively locking against cocking of the striking member when the

pistol is set for safety and unlocked against uncocking the striking member.

11. A pistol comprising a striking member provided with an extension and a lug on the extension on that part of the striking member which is opposite to the striking face, said extension being arcuate in shape and the lug projecting from a casing of the pistol, a trigger, a safety member, and a pawl between the safety member and the striking member and controlled by the safety member, said pawl exclusively locking against cocking of the striking member when the pistol is set for safety and unlocked against uncocking the striking member.

12. A pistol comprising a striking member provided with an extension and a lug on the extension on that part of the striking member which is opposite to the striking face, a safety member, a pawl between the safety member and the striking member and controlled by the safety member, said pawl exclusively locking against cocking of the striking member when the pistol is set for safety and unlocked against uncocking the striking member, and a pair of bridge members on a casing for the pistol to seal the casing around and in the path of movement of said extension. 5 10

ERNST ALTBURGER.
